United States Patent Office.

DANIEL HARMON, OF COLES COUNTY, ILLINOIS.

Letters Patent No. 101,729, dated April 12, 1870.

IMPROVEMENT IN DITCHING-PLOW AND HEDGE-GRADER.

The Schedule referred to in these Letters Patent and making part of the same

To all whom it may concern:

Be it known that I, DANIEL HARMON, of the county of Coles and in the State of Illinois, have invented certain new and useful Improvements in Ditchers and Hedge-Graders; and do hereby declare that the following is a full, clear, and exact description thereof, reference being had to the accompanying drawing making a part of this specification, in which—

Figure 1 is a plan view of my improved device;

Figure 2 is a side elevation, and

Figure 3 is a rear elevation of the same.

Letters of like name and kind refer to like parts in each of the figures.

My invention is designed for making ditches; and

It consists, first, in the means employed for attaching the truck to the plow-beam, and, in connection therewith, for regulating the depth of the furrow;

It also consists in the peculiar construction of the "spreader," whereby it can be adjusted to any desired width; and,

Finally, in the means employed for regulating the draft of the spreader.

In the annexed drawing—

A represents the plow-beam, having secured to and projecting downward from near its rear end an arm, B, to which the plow C, of usual form, is attached.

Extending upward from the front and rear ends of the beam A are two bars, D and E, respectively, to the former of which is pivoted one end of a lever, F, that, extending rearward, is provided with a slot, f, having a suitable size to permit said lever to pass over the bar E.

The lever F is pivoted, near its front end, to or between the upper ends of two standards, G, which are secured within and extend upward from an axle, H, supported by means of suitable wheels, I, so that, by raising or depressing the rear end of said lever, the front end of the beam A is raised or lowered, and the depth of the ditch correspondingly varied.

Suitable corresponding holes, e, being provided within the bar E and lever G, the latter is secured in position, when adjusted, by means of a pin, x, passing through both lever and bar, while the relative positions, fore and aft, of the truck and plow-beam are secured by means of two stay-rods, h, attached to the front end of said beam and to the axle H.

Attached, by means of a hinge-joint, K, to the rear end of the land-side C, is a spreader, consisting of a land-side, L, and mold-board, M, connected together at their front ends by means of a curved rod, N, rigidly fastened at one end to said land-side, and pivoted at its opposite end to said mold-board.

Two wooden bars, O, are pivoted to the mold-board, and extend inward, so as to overlap two metal bars, P, pivoted to the land-side, in which position they are secured together and rendered relatively adjustable by means of pins p passing through corresponding holes, of which a series is provided within, and extends horizontally through each bar.

The land-side L is formed of a steel plate secured to and strengthened by means of wood, and has projecting horizontally outward from near its rear end a plate, l, which serves to hold said land-side steadily in position when in operation.

Extending upward from the land-side L, near its rear end, is a short standard, R, to which is pivoted one end of a bar, S, having upon its opposite end a wheel, T.

The axle or bar S extends inward, with the wheel T resting upon the ground, and is held in place, fore and aft, by means of a rod, t, loosely attached to said axle, and to the front bar O.

Pivoted to the standard R, by means of the bolt s, used for securing thereto the bar S, is a second bar, U, which extends upward and across, and is rigidly attached to said bar S by a brace, V.

A lever, W, is loosely connected at one end to the rear end of the mold-board M by a linked rod, m, from whence it extends forward, and is suspended from the outer end of the bar U by means of a chain, w, said chain being connected to said lever at a short distance forward from its rear end.

It will be readily seen that the wheel T serves as a fulcrum for the lever W, so that, if the front end of the latter be depressed, the mold-board M will be correspondingly raised.

As thus described, the machine is complete, is entirely under control of the operators, and may be quickly and readily adjusted, so as to form a ditch having any desired depth, width, or grade, and, being simple in construction, durable, and not more expensive than ordinary ditching-machines, it is believed that its introduction will prove a public benefit.

Having thus fully set forth the nature and merits of my invention,

What I claim as new, and desire to secure by Letters Patent, is—

The devices employed for connecting together and rendering relatively adjustable the plow-beam and truck, consisting of the bars D and E, the lever F, the divided or double standard G, and the stay-rods h, substantially as shown and described.

Also, the hereinbefore-described spreader, consisting of the land-side L and mold-board M, connected together and made relatively adjustable by means of the rod N and bars O and P, substantially as set forth.

Also, the means employed for regulating the draft of the spreader, consisting of the bar S, the wheel T, the bar U, the brace V, and the lever W, all constructed and arranged to operate substantially as shown, and for the purpose described.

Also, the general construction and arrangement of the various parts of the hereinbefore-described device, substantially as and for the purpose specified.

In testimony that I claim the foregoing, I have hereunto set my hand, this 8th day of December, 1869.

DANIEL HARMON.
